INCINERATOR AND SMOKE-CONSUMING APPARATUS

Gordon H. Hoskinson, 36th Ave. and 13th St.,
Long Island City, N.Y.
Filed Dec. 19, 1960, Ser. No. 76,670
12 Claims. (Cl. 110—18)

The present invention relates to burning apparatus, and more particularly to incinerator apparatus of a new and novel construction capable of burning rubbish, waste material and the like in large volume in a more efficient manner than heretofore possible, and also makes possible the utilization of heat generated by the burner for other useful purposes.

Incinerators have been employed for a great many years as a means for disposing of trash, rubbish, waste material, and the like but have possessed a great many disadvantages. For example, prior incinerators emit a considerable amount of heavy smoke and other obnoxious waste products of combustion into the atmosphere which are quite hazardous to the health of the community in general. Moreover, such waste products of combustion also create an economical problem with respect to maintenance of property in general in the area where the material is burned due to the fact that such products of combustion not only soil virtually everything with which they come into contact but also tend to enhance or hasten the deterioration of the physical property nearby. The waste products of combustion generated which are primarily objected to are in the form of unburned carbon which gives rise to the heavy dark smoke and gases and other obnoxious vapors generated during the burning operation. The large amount of carbon present in the waste products of combustion, and the generated gases, vapors, and the like is due to the incomplete or inefficient combustion during the actual burning of the materials. The inefficient or insufficient combustion may be due to the structure of the incinerator itself, or as a result of insufficient heat in the burning zone to effect an efficient operation, or insufficient oxygen to support the desired degree of combustion which will insure a complete consumption of the material being burned, or a combination of all three.

Another disadvantage possessed by prior incinerators is that such units capable of burning a large volume of waste material are extremely expensive in initial cost as well as upkeep and yet are quite inefficient in operation. Moreover, prior incinerators capable of burning a large volume of waste material are so designed that the residue remaining after burning cannot be readily removed. This results oftentimes in a shut-down of the incinerator with a corresponding cooling thereof in order to permit a cleaning out of the unit before further burning can be effected.

Still another problem with prior incinerators is that the heat generated by the incinerator during the burning of the waste material is totally lost. There has long been a need in industrial plants, commercial establishments of all types, and the like for an incinerator which can be utilized to effect the burning of the desired waste material and yet also can utilize the heat generated for other purposes. Such prior incinerators due to the inefficiency of operation and the waste products of combustion generated have not been able to be employed in such a manner.

Considerable time, effort, and money has been expended over many years towards the development of an incinerator which will function in a more efficient manner and which will provide a more effective combustion of the material to be burned. However, all of these prior attempts to date have not been satisfactory and the problems hereinbefore enumerated with respect to incinerators still exist.

In the elimination of the foregoing and related disadvantages,

2

vantages, it is therefore a principal object of the present invention to provide an incinerator of a new and novel structure possessing a more efficient operation than heretofore capable with prior incinerators.

Another object of the present invention is the provision of a new incinerator that is extremely simple in design and construction, low in cost, and requires virtually no upkeep.

Still another object of the present invention is the provision of an incinerator that does not emit obnoxious waste products of combustion to the outside atmosphere during its operation regardless of the material being burned.

Still another object of the present invention is the provision of an incinerator which will insure a substantially complete combustion of the objectionable waste products of combustion wherein the products emitted therefrom to the atmosphere will not be in a harmful state.

Another object of the present invention is the provision of an incinerator wherein the waste products of combustion generated therein will be consumed prior to the emission of same to the outside atmosphere.

Still another object of the present invention is the provision of an incinerator which can function both as a heating unit as well as an incinerator unit.

A further object of the present invention is the provision of an incinerator unit in which the heat generated therein is utilized for other purposes.

A further object of the present invention is the provision of an incinerator that can be employed to burn a large volume of waste material in an efficient manner.

Yet another object of the present invention is the provision of an incinerator which can remain in continuous operation without requiring a shut-down after a period of time to remove unburned residue present therein.

A still further object of the present invention is an incinerator unit in which the residue remaining after each batch of material has been burned is immediately withdrawn without shut-down of the incinerator.

A further object of the present invention is the provision of new and novel means for retaining the waste material during its burning which enables the residues remaining to be immediately withdrawn without a shut-down of the equipment.

Other and additional objects will become manifest from the ensuing description taken in conjunction with the accompanying drawings.

Broadly stated, the incinerator made in accordance with the present invention comprises a building unit, said building unit including a floor, side walls, a rear wall, a substantially flat roof, and door means hingedly secured to the free end of at least one of said side walls, air inlet means in said rear wall of said building unit, spaced track means extending into the floor of said building unit, cart means for receiving the material to be burned, said cart means being mounted for movement on said track means into and out of said building, said cart means including a plurality of hollow pipe means connected to one another defining a pair of side walls and front and rear walls, at least some of said pipe means having openings therein, one of said pipe means forming said rear wall having at least one nipple extending outwardly therefrom for engagement with said air inlet means of said rear wall of said building whereby air can be passed through the pipes forming said cart to support combustion therein, outlet means in said roof, and exhaust means secured to said outlet means.

To the accomplishment of the foregoing and related ends, the present invention then consists of the means hereinafter fully described and particularly pointed out in the claims, the annexed drawing and the following description setting forth in detail certain means in the carrying

out of the invention, such disclosed means illustrating, however, but one of various ways in which the principle of the invention may be employed.

The present invention is illustrated, by way of example, in the accompanying drawings, in which:

FIGURE 1 is a perspective front elevational view of an incinerator unit made in accordance with the present invention illustrating the insertion of a cart into the unit.

FIG. 2 is a top plan view of the incinerator made in accordance with the present invention with the exhaust stack removed.

FIG. 3 is a side elevation in cross section of the incinerator made in accordance with the present invention illustrating the positioning of the cart within the incinerator during the operation thereof.

FIG. 4 is a front elevation of the cart means employed in the illustrative embodiment of the present invention illustrating the removal of the cart from the rail means.

FIG. 5 is an enlarged fragmentary cross sectional view illustrating the mounting of the tubes in the roof of the incinerator made in accordance with the present invention.

FIG. 6 is a fragmentary side elevation in cross section illustrating a heat exchanger unit employed with the incinerator made in accordance with the present invention.

FIG. 7 is a cross section of the heat exchanger unit taken on lines 7—7 of FIG. 6.

FIG. 8 is a perspective view of the removable heat exchanger core of the heat exchanger unit shown in FIGS. 6 and 7.

FIG. 9 is a fragmentary side elevation view of the stack construction and the secondary combustion zone made in accordance with the present invention.

FIG. 10 is a cross sectional view taken on lines 10—10 of FIG. 9.

FIG. 11 is a fragmentary perspective view of the bottom construction of the frame of the cart made in accordance with the present invention, particularly illustrating the means for distributing air into the incinerator unit to support combustion and to maintain the cart in a comparatively cool state.

FIG. 12 is a fragmentary side elevation in cross section illustrating a modified form of stack construction made in accordance with the present invention.

Reference is now to be had to the drawings, and with particular reference to FIGS. 1-3 wherein a building unit, generally designated by reference numeral 10, is shown. The building unit 10 defines the area or dimensions of the incinerator proper and is to be a fixed and permanent installation. The building unit 10 may be either square or rectangular in configuration, and may be of any desired dimensions dependent upon the volume of waste material to be burned. Moreover, the building unit 10 may be made from any desired material possessing the required structural strength, although the inside surface of the building unit 10 must be of such character that can withstand high and prolonged heat.

The building unit 10, as illustrated, comprises a floor 11 which may be in the form of any base construction having a refractory surface bonded thereto. However, it is possible, if desired, to employ a floor made entirely of refractory material using, for example, bricks made of fire clay or the like. The refractory material or surface to be employed with or as the floor 11 may be any suitable material capable of withstanding high, intense, and prolonged temperatures, such as, for example, fused silica, fire clay, fused alumina, fused refractory material, kaolin refractory material, magnesite, mullite refractory, asbestos, silicon, carbide, etc. Any of the foregoing refractory materials may be applied or laid as a surface or facing layer on the floor base, such as, for example, concrete, steel, or the like, or, where such materials are capable of being poured or laid in brick or block form, the base may be dispensed with. A pair of spaced, parallel grooves 12 are centrally positioned in the floor 11 and extend from the front to the back thereof. Each of the grooves 12 has a track or

rail element 13 positioned therein with each track extending outside and beyond the front edge of the floor 11. This construction defines a railway track assembly into and out of the building unit 11 which enables the material to be burned to be brought into and out of the building unit 10 in a manner to be more fully described hereinafter.

The building unit 11 is provided with a pair of vertical side walls 14 and 15 built along each side edge of the floor 11 which defines the vertical dimensions of the building unit 10. The side walls 14 and 15 may be made of any suitable material and in any desired manner which will provide the necessary structural strength, but the inside face thereof must possess a refractory facing in order to protect the side walls against the intense heat generated therein. As illustrated, the side walls 14 and 15 are made of laid concrete block, with the inside surface thereof being provided with a refractory facing which may be any of the materials hereinbefore enumerated for use in the floor 11. It is to be understood that the side walls 14 and 15 may be made completely of refractory block or brick, but under such circumstances reinforcing will be required in order to provide the necessary strength. Alternatively, the side walls may be formed by framing of structural iron or steel spanned on the outside by metal paneling and having the frame filled with refractory material of a thickness corresponding to the width of the structure member. The thickness of the side walls 14 and 15 regardless of how made and the materials used must be sufficient to withstand the intense and prolonged heat generated within the building unit 10.

As is to be understood, the side walls 14 and 15 are made of laid concrete block, with the inside surface thereof being provided with a refractory facing which may be any of the materials hereinbefore enumerated for use in the floor 11. It is to be understood that the side walls 14 and 15 may be made completely of refractory block or brick, but under such circumstances reinforcing will be required in order to provide the necessary strength. Alternatively, the side walls may be formed by framing of structural iron or steel spanned on the outside by metal paneling and having the frame filled with refractory material of a thickness corresponding to the width of the structure member. The thickness of the side walls 14 and 15 regardless of how made and the materials used must be sufficient to withstand the intense and prolonged heat generated within the building unit 10.

A rear wall 16 is provided along the rear edge of the floor 11 and is connected or united to the rear vertical ends of the side walls 14 and 15. The rear wall 16 may be made in the same manner using the same materials as the side walls 14 and 15. The inside facing of the rear wall 16 will likewise be provided with a refractory layer of sufficient width in the same manner and for the same purpose as the refractory layer of the side walls 14 and 15. The rear wall 16 is provided with at least one opening 17 in its lower portion thereof and provides means for providing air to support combustion in a manner to be described more fully hereinafter.

To provide the necessary structural strength to the building unit 10 and to enable the mounting of doors and a roof to the building unit 10, structural members 18 and 19 are secured, respectively, to the front vertical end of each of the side walls 14 and 15 by any suitable means, such as, for example, anchoring during the formation of the wall or the like. The structural members 18 and 19 may be made of any suitable material and in any desired form, the preferred material being structural steel or iron, although any other material possessing the desired strength may be employed equally as well. The structural members 18 and 19 should be so positioned with respect to the end edges of the walls 14 and 15 that when the doors are closed in a manner to be more fully described hereinafter, the structural members 18 and 19 will not be in direct engagement with the heat generated within the building unit 10. The structural members 18 and 19 are connected to one another by a top transverse structural member 20 secured to the top ends of each by bolting, welding, or the like, thereby spanning the width of the building unit 10 and aiding in imparting the required structural strength thereto. The top transverse structural member 20, as illustrated, is in the form of an I-beam and may be made from structural steel, iron, or any other metal having the required strength. The structural member 20, as shown, extends above the top edge of the side walls 14 and 15 in order to provide strength for the roof.

This arrangement of the structural members 18, 19, and 20 just described defines a framework which, in addition to providing structural strength to the building unit 10, also provide a door frame for the mounting of the doors, generally designated by reference numerals 21

and 22, to the building. The doors 21 and 22 are each in the form of a rectangular frame having structural metal vertical elements 23 and 24, and top element 25, and a bottom element 26, which are connected at their respective free ends by welding or the like to complete the desired frame. The outside face of the frames forming the doors 21 and 22 is each provided with a covering sheet or sheath 27 of any suitable metal, such as, for example, steel or iron, which is secured to the formed frame of the doors 21 and 22 by welding, riveting, bolting, or the like. The inside of the frame of the doors 21 and 22 is provided with refractory material 28 which completely seals the entire open frame portion of the doors 21 and 22. The refractory material may be any employed with the side walls 14 and 15 or the rear wall 16, and is of a thickness corresponding to the thickness of the framework of each of the doors 21 and 22. This construction results in a facing of refractory material on the inside face of each door 21 and 22. The doors 21 and 22 must be so dimensioned that when in a closed state to seal the building unit 10, the refractory material of the doors 21 and 22 will be the only material of the doors which will be in direct contact with the heat generated within the building unit 10.

Each of the doors 21 and 22 is secured to the structural members 18 and 19, respectively, by a pair of upper and lower hinges 29 which are of the heavy duty type and may be of any desired construction since hinges of this character are readily available on the open market. Each of the doors 21 and 22 is further provided with a handle 30 which is preferably bolted to the frame member 23 through the metal covering sheet 27 and serves as a means to open and close the doors. The door construction just defined is one which provides mating doors 21 and 22 hingedly connected to each side edge of the building unit 10 through the structural members 18 and 19, and which, when in a closed state, provides an inner surface of refractory material for the building unit 10.

A heat exchanger unit, generally designated by reference numeral 31, is positioned within the building unit immediately adjacent its top surface and is capable of providing heat for performing one or more useful functions in a manner to be more fully described hereinafter. The heat exchanger unit 31 comprises a plurality of pipes 32 which extend completely across the side walls 14 and 15 of the building unit 10 in closed spaced, parallel relationship to one another. The pipes 32 have their free ends extending just beyond the outside vertical plane of the side walls 14 and 15, respectively. As illustrated, the pipes 32 extend the entire length of the building unit 10 in transverse relationship thereto with the exception that pipes do not extend across the exhaust openings in the roof. The purpose for not placing pipes 32 beneath the openings in the roof is in order to insure a full draft or exhaust of the heat and waste products of combustion out through such opening. However, it is to be clearly understood that, if desired, the pipes 32 can extend the full length of the building unit 10 in closely spaced, parallel relationship with respect to one another regardless of the exhaust openings.

As shown in FIG. 5, the free ends of the pipes 32 which extend just beyond or outside the vertical plane of the outside face of one of the side walls, such as, for example, side wall 14 of the building unit 10, are in operative association with an air inlet duct or header 33 for receiving air or other fluid medium for transmission therein a manner more fully described hereinafter. The air inlet header 33 will extend a distance substantially equal to the length of the side walls of the building unit 10, or a distance sufficient to encompass the free end of all of the pipes 32. One end of the air inlet duct 33 is closed with the opposite end thereof being open, with an air blower 34 of conventional design being mounted therein to blow air into the air inlet duct 33, and hence into the pipes 32 thereby insuring forced circulation of the air. The oppo-

site free end of each of the pipes 32 likewise extends just beyond the vertical plane of the outside face of opposite side wall of building unit 10, and is associated with an air outlet duct or header 35 for receiving the air being blown through the pipes 32.

The outlet header 35 possesses substantially the same dimensions as the inlet header 33 and is positioned in a similar manner on the opposite outer face of the side of the building unit 10 for its entire length. As shown, the air outlet header 35 is closed at both ends and has a pair of spaced outlet means 36 on the upper surface thereof which will permit the air, after it has been passed through the tubes 32, to pass outwardly therefrom. This air passing through the outlet 36 will be employed in this illustrative embodiment of the invention to support combustion in a secondary zone of combustion in a manner to be more fully described hereinafter. However, the illustrative form of air outlet header shown herein may be modified to accomplish various other purposes, as will be described more fully hereinafter.

The air inlet duct or header 33 and the air outlet duct or header 35, as shown, are not directly secured to the opposite free ends respectively of the bank of pipes 32, but rather, form a closed area into which the pipes extend. The air inlet header 33 and the air outlet header 35 are shown as being rectangular in cross section, with one side being open defining a U-shaped channel header. Moreover, the headers 33 and 35 possess a diminishing cross section from rear to front, or from the inlet end to the closed end of the inlet header 33, to insure an adequate volume of air being passed through the heat exchanger 31. The free ends of each leg of the U-shaped headers 33 and 35 are turned outwardly at right angles thereto forming upper and lower connecting lips 37 which are employed for mounting the air inlet header 33 and the air outlet header 35 to the building unit 10 in a manner to be more fully described hereinafter. This construction results in the free ends of the pipes 32 having complete access to the air inlet header 33 and the air outlet header 35 without being connected thereto.

The foregoing heat exchanger construction will be found advantageous since it enables the ready withdrawal and replacement of one or more of the tubes 32 when the occasion arises. This can be accomplished by detaching one of the air carrying headers from the building unit 10, withdrawing the tube or tubes 32 to be replaced, and reinserting a new tube or tubes. While the foregoing arrangement just described is preferred, it is to be understood that other constructions may be employed equally as well. For example, the inlet and outlet headers may be cylindrical in cross-section and the tubes will be connected thereto by a slip joint construction, welding, or the like. This type of header construction for the heat exchanger 31 will be of particular utility in the event a fluid medium other than air, such as, for example, water, is passed continuously through a heat exchanger.

A preferred manner for positioning the heat exchanger 31 in the housing unit 10 is to secure a metal plate 38 in permanent relationship to each of the outer faces of the side walls 14 and 15 adjacent the top edge of each, thereby providing an outer vertical form. The metal plates 38 extend above the top edge of the side walls 14 and 15 and constitute a vertical continuation thereof. The vertical height of the side metal plates 38 above the side walls 14 and 15 is determined by the number of pipes that are to be employed in vertical arrangement since such pipes constitute the means for holding the free ends of the pipes 32 in place during the formation of the heat exchanger assembly 31. To effect this positioning of the pipes 32 in place, the outside metal plates 38 are each provided with holes or openings equal to the number of pipes to be used, and which will have a diameter corresponding to the outside diameter of the pipes 32 to be employed, with the free ends of pipes 32 being held in each plate by a press fit. An inner vertical form plate

39 is spaced inwardly of each of the outer metal plates 38 in substantially parallel relationship therewith, and each is secured to or is in engagement with the inner face of the side walls 14 and 15 adjacent the top edge thereof, and each extends upwardly therefrom for a distance corresponding to that of the outer metal plates 38. The inner form members 39 are each provided with openings therein which conform to and are in axial alignment with the openings in the outer metal plates 38 such that the tubes 32 likewise extend through the inner form plates 39 and the outer form plates 38.

The assembly just described defines a pair of spaced, form troughs which extend along the top surface of each of the side walls 14 and 15, with the pipes 32 spanning the width of the two side walls in vertically spaced relationship and being held in a fixed state. Concrete or other refractory material is then poured in each of the form troughs along the top of each of the side walls 14 and 15, and permitted to harden. This construction results in a complete embedding of the pipes 32 in the hardened concrete but yet will enable one or more of the tubes to be withdrawn when the necessity arises due to the fact that the concrete does not bond to the metal surface of the pipes. The inner form plates 39 are made of combustible material such as, for example, plywood, heavy kraft paper, cardboard, and the like, and are not removed after the concrete is set. Rather, the inner form plates 39 will be consumed by burning during the first operation of the incinerator unit. The air inlet header 33 and the air outlet header 35 are then secured to the outside surface of its corresponding metal plate 38 by means of screws or the like extending through the upper and lower lips 37 of the headers 33 and 35.

It will be found advantageous to provide a heat baffle plate 40 which will extend across the face of the heat exchanger assembly 31 for the width of and at the front end of the building unit 10. The purpose of the heat baffle plate 40 is to provide a vertical barrier to insure the retention of heat in the heat exchanger zone, particularly when the doors of the building unit 10 are opened to permit withdrawal of burned residue and to add further waste material to be burned. The baffle plate 40 will have each end secured in a vertical state to the top surface of or to the end edge of the front of the side walls 14 and 15, thereby resulting, as shown, in a metal plate having a vertical height sufficient to shield the tubes 32 and which extends across the entire width of the building unit 10.

Of course, it is to be understood that the rear wall 16 is to possess a vertical height corresponding to that of the side walls 14 and 15 and the outer metal plates 38 combined therewith. This can be accomplished by mounting detachable forms to the inner and outer face of the rear wall 16 adjacent the top edge thereof with the forms extending upwardly therefrom in spaced, parallel relationship to one another for height equal to that of the metal plates 38. Thus when the concrete or other refractory material is poured in the form troughs on the side walls 14 and 15 to embed the pipes 32 therein, the trough form on the rear wall 16 likewise can be filled with concrete at the same time thereby bringing the vertical height of the rear wall 16 to the desired level.

While the foregoing description is of a particular and preferred manner for associating the heat exchanger unit 31 to the building unit 10 for accomplishing its intended function, it is to be clearly understood that there are a wide variety of other ways in which the heat exchanger unit 31 may be secured within the building unit 10. For example, the heat exchanger unit 31 may be in the form of a single unit and be positioned completely within the housing unit 11 to the roof of the housing unit by bolting, by brackets, or the like. The air inlet header could then extend through the rear wall 16 with the air outlet header being positioned completely within the unit 10, with the outlet end thereof extending inwardly through

the roof. Another manner of positioning the heat exchanger 31 shown herein can be accomplished by forming the required number of openings equal to the number of pipes to be employed in the side walls 14 and 15 in axial alignment with one another. The tubes 32 are then inserted through the formed openings in the side walls and the air headers 33 and 35 may then be associated therewith in any desired manner. Therefore from the foregoing it is believed quite obvious that the present invention is not to be in any way limited by the illustrative embodiment of the exchanger unit 31 and its manner of mounting shown herein.

The roof 41 is in the form of a flat planar roof spanning the side walls 14 and 15 and the rear wall 16, with its inner face lying immediately above the pipes 32 of the heat exchanger 31. The roof 41 is provided with a pair of spaced openings 42 which extend in a vertical plane with respect to the building unit 10 to provide exit means for the heat and waste products of combustion generated within the building unit 10 during the burning of material therein. The roof 41 may be made of any of the refractory materials hereinbefore enumerated, but must possess sufficient structural strength for the building unit 10 to result in a sturdy, permanent structure. For example, concrete can be employed as the roof structure and should be of the reinforced kind and may be poured during the pouring operation hereinbefore described with respect to the securing of the heat exchanger unit 31 to the building unit 10. This may be accomplished by providing the desired forms during the positioning of the metal plates 38 and the inner form member 39, with all of the concrete being poured at once. It is to be clearly understood, however, that the roof structure 41 may be made in any manner and of any desired refractory material that will possess sufficient strength in and of itself or by reinforcement, and which will withstand the intense and prolonged heat generated within the building unit 10 during the burning of material therein.

A stack support structure, generally designated by reference numeral 43, is mounted to the top surface of the roof 41 and functions to support the stack structure and other associated apparatus therewith independent of the refractory roof structure 41. As illustrated, the supporting structure assembly 43 includes a structural flange element 44 secured to the outside face of the rear wall 16 immediately adjacent the top edge thereof such that the top, outwardly extending flange portion thereof will be just above the top surface of the refractory roof 41. If the stack is to be excessively heavy, vertical structural supports may be secured to each end of the flange element 44 to impart additional strength thereto. A pair of structural supporting top frame elements 45 and 46 are positioned over the roof 41 in parallel relationship with respect to one another and are in inwardly spaced relationship from the side walls 14 and 15 of the building unit 10. The structural top frame elements 45 and 46 are illustrated as being positioned such that they will run from front to rear of the building unit 10, with the rear free end of each of the structural frame elements 45 and 46 being secured to the top surface of the flange element 44 by any suitable means, such as, for example, welding, bolting, or the like. The opposite forward free ends of the top frame elements 45 and 46 are secured to the transversely positioned I-beam member 20 likewise by welding, bolting, or in any other desired manner. This construction results in a supporting frame assembly 43 which can support all elements of the stack structure and related apparatus independent of the roof structure. It is to be clearly understood that this construction is shown for illustrative purposes only and, while preferred in general overall operation, the stack and other apparatus can be carried solely by the roof, providing the roof is reinforced sufficiently.

As hereinbefore indicated, the refractory roof 41 has a plurality of exhaust openings 42 therein to permit the escape of heat and other waste products of combustion from the building unit 10 in which the burning will occur. As shown, there are two pairs of two openings or outlets 42 each formed in the roof 41 with the front two openings being utilized as a unit and the rear two openings likewise functioning as a unit. An outlet pipe element 47 is positioned within or associated with each of the two pairs of two openings 42 and extends upwardly therefrom in axial alignment therewith, and are connected by brackets or the like to the top frame elements 45 and 46. This construction results in a forward or front pair of spaced outlet pipe means 47 and a rear pair of spaced outlet pipe means 47 which extend upwardly from the top surface of the roof 41 for a very short distance. It is to be clearly understood that the two pairs of two outlets shown herein are illustrative in character only, since any number of pairs of openings may be provided in the roof depending upon the size of the building unit.

A pair of heat exchange units, generally designated by reference numeral 50, is secured respectively to the upper free ends of the front pair of outlet pipe means 47 and the rear pair of outlet pipe means 47. A description of one of the heat exchangers 50 will now be given with such description being equally applicable to the other heat exchanger 50 connected to the other pair of outlet pipe means 47.

The heat exchanger 50 comprises a central, cylindrical outer shell body 53 of heavy gauge metal which is connected to the spaced pair of outlet pipes 47 in transverse relationship with respect thereto. The transversely extending heat exchanger 50 is covered by an arcuate shell 51 which is bent around the heat exchanger 50 in spaced relationship thereto. The shell 51 is held in spaced relationship from the heat exchanger 50 by means of spacer strips 52 forming a circumferential axial passageway between the shell 51 and the heat exchanger 50. The inner cylindrical shell body 54 similarly made of heavy gauge metal is detachably positioned within the outer shell body 53 in spaced relation therewith. This construction defines a tubular member having an essential passageway extending therethrough. The association of the outer and inner shell bodies 53 and 54 results in an airtight area between the two bodies with the exception of the two inlet openings in the outer shell body 53 to receive inlet pipes 47 and the outlet opening in the outer shell body 50 functions as an outlet for the waste products of combustion.

The forward end of the inner shell body 54 is provided with an outwardly flaring rim portion 55 with the outward terminal end of the flared rim portion 55 provided with a reversely turned perimetral flange portion 56 forming a lip to receive the circular peripheral end of the outer shell body 53. The opposite end of the outer shell body 53 is provided with an inwardly inclined rim portion 57 which, in turn, is provided with a peripheral flange portion 58 to receive the opposite terminal end of the inner shell body 54.

The inner shell body 54 is preferably readily detachable from the outer shell body 53 to enable the units to be more easily cleaned from collected carbon and the like in a manner to be more fully described hereinafter. To separate the tubular member, the inner shell body 54 is merely pulled outwardly, thus freeing the perimetral flange portion 56 from one end of the outer shell body 53 and at the same time freeing the opposite terminal end of the inner shell body 54 from the flange portion 58 of the outer shell body 53. To assemble the inner shell body 54 to the outer shell body 53, the former is inserted in the pipe until its forward terminal end engages the flange portion 58 of the outer shell portion 53. Simultaneously, when this occurs the flange portion 56 of the inner shell body 54 tightly engages the terminal end of

the outer shell body 53, thus locking the bodies in airtight relationship. While this is the preferred construction, it is to be understood that the inner and outer shell bodies 53 and 54 may be permanently secured to one another in spaced relationship.

The inner shell body 54 is provided with a plurality of angularly disposed baffle plates 58, 59, 60, and 61 on the outside surface of the inner shell body 54, and are so positioned with relationship to the inlet openings 47 and the opposed outlet openings of the airtight area between the inner and outer shell bodies 53 and 54 so as to provide a controlled, tortuous passageway for the smoke and heat to travel as it comes from the building unit 10, thereby insuring a proper draft and more efficient burning as well as providing an excellent heat transfer relationship between the elements. The baffle plates 58, 59, 60, and 61 have a height such that the outer edge of each baffle plate will form substantially a seal with the inner surface of the outer shell body 53 to insure the necessary controlled passageways for the smoke.

The baffle plates 58 and 59 are curved around the lower half of the inner shell body 54 and extend upwardly in inclined relationship around the inner shell body 54 on either side thereof to a point short of the top surface 25 leaving a passageway at the top of the shell body 54 at opposite ends thereof. The baffle plates 58 and 59 are inclined downwardly in the direction of one another adjacent opposite ends of the inner shell body 54, with the lower terminus of each baffle plate ending just above 30 the inner inside edge of each of the outlet pipes 47 and extending around and upwardly therefrom in inclined relationship to force the smoke from each of the outlet pipes 47 upwardly and outwardly to the passageway formed at the top surface of the shell body 54 adjacent each end 35 thereof.

The baffle plates 60 and 61 are curved around the upper half of the inner shell body 54 and are each spaced inwardly from the baffle plates 58 and 59 and are inclined such that they are in substantially parallel relationship 40 with the baffle plates 58 and 59. Each free end of the baffle plates 60 and 61 terminates at a point about midway on each side of the inner shell body 54, with each end of the baffles being spaced below and in substantial alignment with the outside edge of the exhaust outlet opening, thereby forming a spaced vertical outlet passageway for the smoke and gases. The arrangement of the baffle plates 58, 59, 60, and 61 is such that the smoke passing upwardly from each of the outlet pipes 47 will be carried outwardly and upwardly on either side of the inner shell body 54 by means of the baffle plates 58 and 59, 45 and pass through the formed passageway of each top surface. The smoke will then strike the top surface of each of the baffle plates 60 and 61 and will be directed downwardly and inwardly on either side of the inner shell body 54 until the smoke reaches the vertically formed exit 50 passageway. The smoke will then pass upwardly through the exhaust outlet of the outer shell body 53.

Another advantage of this construction is that with this form of the heat exchanger 50, cleaning can be accomplished in a relatively short time. To clean the heat exchanger housing 50, the inner shell body 54 is merely pulled outwardly from the outer shell body 53 in the manner hereinbefore indicated. This operation results in the inclined baffle plates 58, 59, 60, and 61 scraping the inner surfaces of the outer shell body 53, thereby removing 55 carbon and the like during the withdrawing operation. The inner shell body 54 is then cleaned by washing or the like with the inner surface of the outer shell body 53 being wiped clean. The inner shell body 54 is then inserted in the same manner as hereinbefore indicated.

While any suitable baffle plate construction may be employed to divide the baffle plates 58, 59, 60, and 61, a particular and preferred construction consists of angled sheet metal in which the base thereof will be secured to 59 the outer surface of the inner shell body 54. The vertical

portion of the angled metal, which will function as the baffle plates, will be provided with a plurality of vertical slits such that when the sheet metal is curved to the contour of the inner shell body 54, the slit portion of the sheet metal will be expanded, resulting in a plurality of small, V-shaped notches. This structure is shown in detail in my United States Patent No. 3,044,460, issued July 17, 1962. The advantage of this particular arrangement is that it will provide a plurality of small openings through which heat will seep to heat the opposite side thereof and will facilitate the passage of smoke and heat through the tortuous path hereinbefore defined. While this is a particular and preferred construction, it is to be clearly understood that any suitable baffle plate construction may be employed which will result in the formation of the desired tortuous path.

A blower fan 62 is positioned at one end of the transverse heat exchanger housing 50 for blowing air therethrough in transverse relationship to the path of the heat, gases, and smoke to pick up heat generated in heat exchange relationship for blowing same in a hot state out through the opposite open end thereof. The diameter of the fan blade of the blower 62 is greater than the diameter of the outer shell body 53 and just slightly less than the inside diameter of the housing shield 51. This arrangement insures a blowing of air not only through the inner passageway of the inner shell body 54, but also around the outside surface of the outer shell body 53, thereby insuring excellent heat exchange relationship. The blower 62 is protected by a heavy metal screen 63 which is tightly positioned at the end of the housing shield 51 to which the blower is mounted. The blower 62 is actuated by electric power, not shown, and is so timed as to be operable only during the actual operation of the incinerator.

While the heat exchanger housing assembly 50 is a particular and preferred one, it is to be clearly understood that other heat exchanger means may be employed. For example, radiator type heat changers may be positioned over each pair of exhaust outlets 47, with each heat exchanger being provided with a blower. In this type of operation, the hot gases will pass up through each heat exchanger, transferring its heat thereto, with air being blown through the heat exchanger where it is warmed by the hot gases and then passed outwardly through the opposite end of the heat exchanger.

To provide a constant heat source to facilitate the transfer of heat generated by the incinerator to the air-stream created by the blower 62, a removable heat trap member 64 is centrally positioned within the inner shell body 64 in spaced relationship thereto. The heat trap member 64 is in the form of an elongated tube 65 with each end thereof enclosed by a pointed nose portion 66. Inlet means 67 and 68 are provided at spaced points on the under surface of the heat trap member 64 and in alignment with the pipe means 47. This construction results in the formation of a closed circuit heat trap in which heat will be continually rising virtually directly from the fire area. Thus as air is blown through the transverse heat exchanger 50, the air will be continually heated by passage over the heat trap member 64.

The function of the pair of heat exchangers 50 illustrated herein is for the purpose of utilizing the heat generated during the operation of the incinerator so that it may be transmitted to function as a warming medium. This may be accomplished by providing an outlet duct (not shown) to the air outlet ends opposite the fan of each of the heat exchangers 50. The outlet duct in turn would be connected to conventional air ducts (not shown) which would extend to the area desired to be heated. Alternatively, the heat exchangers 50 may be employed to provide hot water to any given area. To accomplish this, the inner central cylindrical shell body 54 is withdrawn and replaced with a bank of water carrying tubes through which water will be continuously circulated.

For a full description of such a hot water heater system that may be employed in the present invention reference is to be had to the copending application Serial No. 37,771, filed June 21, 1960, now Patent No. 3,125,158, in which such a heat exchanger water unit and its operation with respect to burning apparatus is disclosed.

While two heat exchanger units 50 have been disclosed herein, it is to be clearly understood that the number of heat exchanger units to be employed will be dependent upon the size and capacity of the incinerator unit. In general, there will be one incinerator unit for each pair of outlets in the roof, although with a small capacity incinerator unit it is possible that a single heat exchanger unit can be employed with a single outlet in the roof of the incinerator. Therefore, the present invention is in no way limited to any particular number of heat exchanger units, but as many may be employed as will be necessary to fully utilize the heat generated by the incinerator which, if it were not for such heat exchangers, would otherwise be wasted.

Each of the heat exchangers 50, as hereinbefore indicated, is provided with an exhaust outlet 69 in the top of the outer shell body 53 which is in opposed relationship to the inlet means which are secured to the pair of pipe outlets 47. The arcuate shield 51 surrounding the outer shell body 53 likewise will be provided with an opening which is in axial alignment with the opening in the outer shell body 53. An outlet stack or pipe means 70 is positioned in the exhaust outlet 69 of each of the heat exchangers 50 and extends upwardly therefrom in transverse relationship thereto for a comparatively short distance. The upper free end of the outlet pipes 70 from the heat exchanger is connected to an expansion collar 71 which, in turn, is secured to a frame support trapezoidal in configuration, generally designated by reference numeral 72, which serves as support means for the exhaust stack and the related apparatus in association therewith.

The trapezoidal shaped support member 72 includes an upper, rectangular-shaped frame portion 73 which is so dimensioned that it will span the distance between outlet pipe means 70 of the heat exchangers 50 and extend just beyond on either side thereof. Similarly, the width of the top frame portion 73 will be just greater than the width of the expansion collars 71 to which the free ends 40 of the outlet pipe means 70 are secured. This construction results in a rectangular upper frame support member 73 that is centrally positioned above but is of less width and length than the top support frame members 45 and 46. The top frame support portion 73 is connected to the top frame support members 45 and 46 respectively, by support legs 74 which extend from each corner of the top frame portion 73 in inclined relationship therewith and are connected to the top structural members 45 and 46 in any suitable manner, such as, for example, welding, bolting, or the like. The entire frame of the trapezoidal shaped support member 72 may be enclosed to prevent heat loss from the heat exchangers 50 and the outlet pipe means 70 by providing removable face panels 74a which will be connected to the four inclined legs 74. This assembly results in a very rigid support of the stack assembly and the heat exchanger unit 50.

Each of the outlet members 70 of the heat exchanger 50 is provided with a side opening just below the upper free end of each and prior to engagement of same with the expansion collar 71. The following description will be had with respect to the function of the opening in one of the outlet means 70, but it is to be understood that the function described will be the same for the opening in the other of the outlet means 70. The purpose of the side opening in the outlet pipe member 70 is to enable the attainment of a secondary combustion zone therein for the further burning of the waste products of combustion generated during the operation of the incinerator.

To achieve the secondary combustion zone, a fuel and air pipe assembly, generally designated by reference numeral 75, is connected at one end to one of the outlet openings in the air outlet header 35 of the heat exchanger 31, with the opposite end of the air and fuel pipe assembly extending upwardly into the outlet member 70 through the side opening formed therein.

The air-fuel pipe assembly 75 includes a pipe line which may be a plurality of pipes connected to one another, or a single continuous line. As shown the fuel pipe assembly 75 comprises a lower vertically extending pipe element 76 which is secured to and extends upwardly from the outlet opening in air outlet header 35 with its opposite end connected to a lower horizontally extending pipe element 77 by means of an elbow joint 78. A vertically extending upper pipe element 79 is secured to the free end of the horizontal pipe 77 by means of an elbow joint 80, with its opposite end connected to a 45° elbow joint 81. The elbow joint 81 is connected by means of a short pipe nipple 83 to a coupling joint 82 which, in turn, is connected with a terminal feeder pipe element 84 in which the free end thereof extends into the outlet 70 through the opening formed therein. A fuel inlet line 85 is secured at one end in tangential relationship to the fuel feeder pipe element 84 prior to entry in the outlet pipe 70 with the opposite end thereof connected to a fuel source (not shown). The fuel that is to be employed in the air fuel pipe assembly 75 may be gas, oil, or any other material capable of being placed in a gaseous or atomizable state. The free end of the fuel feed pipe 84 may be provided with a jet or diffuser plate which will place the air and fuel mixture being passed into the outlet pipe 70 of heat exchanger 50 in a state such that it will be thoroughly admixed with the products of combustion arising through the outlet pipes 70.

An igniter member 86 is mounted to the outside surface of the outlet pipe 70 and extends through the wall thereof and above the discharge end of the terminal feeder pipe element 84. The igniter member 22 may be secured to the pipe 70 in any suitable manner, such as, for example, by threading the openings in the wall of the pipe and then threading the igniter member 22 thereinto. As illustrated, the igniter member 86 is in the form of a conventional spark plug which is threaded into the threaded openings of the pipe 70, with the spark gap end resting above this discharge end of the terminal pipe element 84. The opposite end of the spark plug 86, which is the contact or terminal end thereof, is connected to an electrical lead line 87 which is, in turn, connected to a suitable power source, such as, for example, a battery or the like, since the fuel igniter will only be used intermittently when needed to ignite the air-fuel mixture dispensed into the pipe 70 to establish the secondary combustion zone.

It will be found desirable in many instances, after a period of time in which the secondary combustion zone has been in operation, to cut off the fuel since the stack temperature in the immediate area of the secondary combustion zone will be sufficiently high to permit a self-ignition of the fuel-air mixture and the waste products of combustion. It will be necessary, however, particularly under such circumstances to have the secondary combustion zone in reasonably close proximity to the outlet end of the fire burning area proper in order to prevent any unnecessary heat loss. However, under general operation, it is preferred that the fuel be continuously burned during the operation of the unit.

The construction just described results in a secondary combustion zone which is in the upper end of the outlet pipe 70 and which will extend above the expansion collar 71. To retain the secondary combustion zone in the desired confined area, an upper outlet pipe 88 is connected at one end to the expansion collar 71 and thus to the outlet end of the outlet pipe 70 and extends upwardly therefrom in axial alignment therewith. The upper outlet pipe 88 from its point of attachment increases in cross-sectional

width for a short distance upwardly to provide an expansion area for the secondary combustion zone. The upper outlet pipe 88 will extend upwardly for some distance since it will constitute a portion of the exhaust stack or chimney of the incinerator. To insure a complete draft of the waste products of combustion, a draft inducer 88a may be mounted on the upper outlet pipe 88, if such appears necessary. In the secondary combustion zone, the waste products of combustion pass out of the heat exchanger 50 and into the outlet pipe, wherein they will be admixed with the fuel and hot air mixture being blown thereinto, and which will be burned in a comparatively small area by ignition of the fuel. This secondary combustion zone will effect a further burning with fresh air and fuel of the waste products of combustion which would otherwise pass out to the atmosphere in a harmful or objectionable state. The construction just described to effect the secondary combustion zone must not be positioned too far above the discharge outlet of the heat exchanger 50 or the outlet end of the building unit 10 since it will be found advantageous in the overall efficiency of the incinerator to have the waste products of combustion burned while still in a relatively hot state with no material amount of heat being dissipated to the outside surface through the pipe member 70. A close association of the parts just described will further insure no heat loss of the hot air obtained from the heat exchanger 31.

The construction providing the secondary combustion zone for the waste products of combustion just described results in a material burning or otherwise partially converting the waste products of combustion generated by the burning of the waste material. However, such products of combustion still are not in a state that they can be passed to the atmosphere without creating problems. Thus, in order to accomplish this desired result of rendering the ultimate waste products of combustion into a suitable state in which they can be expended into the outside atmosphere, a third combustion zone will be necessary to effect a further burning of the waste products of combustion before such products can be passed to the atmosphere.

To provide the third combustion zone, an outer upper stack 89 is secured to the upper outlet pipe or inner stack 88 above the secondary combustion zone and extends upwardly therefrom in spaced enveloping relationship with respect to the inner outlet pipe 88. The outer stack 89 may be made of the same metal as the inner stack 88 and is secured thereto in spaced relationship by means of connecting rods 90 extending therethrough at various convenient points. The outer stack member 89 extends upwardly and beyond the outlet end 91 of the inner stack member 88 and constitutes a final exit stack for the ultimate waste products of combustion. The outer stack member 89 is spaced circumferentially from the inner stack member 88 for a distance sufficient to provide a circumferential air channel or passageway therebetween in which air will rise vertically. Thus the formed air channel therebetween will provide air at the terminal or exit end 91 of the inner stack member 88, with this zone just above the terminal end constituting the third combustion zone to effect the final burning of the waste products of combustion such that they can be emitted to the atmosphere in a completely safe and substantially clean state.

In order to provide a suitable third combustion zone, the inner stack member 88 must be of a sufficient height such that the air passageway formed between the inner stack member 88 and the outer stack member 89 will be sufficiently long to effect a proper heat transfer between the waste products of combustion generated in the secondary combustion zone in order to heat the air passing upwardly to such a temperature that self-ignition will be possible between the waste products of combustion passing from the exit end 91 of the inner stack member 88 and the incoming air converging therewith at the exit end.

Thus the outer stack member 89 must not be spaced from the inner stack member 88 at too great a distance such that the volume of air passing upwardly therebetween in the formed air passage will be too large in volume to be heated. The spacing should be sufficient to permit a volume of air therein sufficient to support the further burning of the waste products of combustion, but will be of a volume insufficient to receive the heat transferred from the inner stack member 88 such that the air will not be heated to the required temperature. From the foregoing, it is believed obvious that the inner stack member 88 must be of a length and diameter and the outer stack member 89 must be so spaced with respect thereto that the heat transfer between the inner stack member 88 and the volume of air passing upwardly therebetween will be effected such that when the air passes above the terminal or exit end 91 of the inner stack member 88, the air will admix with the waste products of combustion and will be at a temperature such that the admixture will immediately ignite thereby effecting the desired further burning of the waste products of combustion. In the general operation of the stack unit described hereinbefore, the effect of the further burning or conversion of the waste products of combustion in the third combustion zone results in the final products of combustion being placed in a condition such that they can be passed to the atmosphere in a completely safe and unobjectionable state. As hereinbefore indicated, the heat exchanger and stack assembly just described will be duplicated since two pairs of outlets are provided in the building unit 10. Thus the incinerator will have two stack and heat exchanger assemblies for the incinerator. However, the invention is not to be limited to two, as hereinbefore indicated.

It is to be clearly understood that the overall assembly of associated parts defining the heat exchanger assembly and the stack assembly to effect the desired utilization of heat and achieve the second and third combustion zones is for illustrative purposes only since such an assembly is capable of material modification. For example, the pair of heat exchangers 50 may be eliminated, if desired, where no utilization of the heat generated by the incinerator is to be made. However, it is preferred from a general efficiency operation and for dual functionality to employ the heat exchangers 50 or some other type heat exchanger with the incinerator unit due to the fact that the heat exchangers will function as carbon traps and will normally catch and retain a portion of the carbon passing upwardly therein carried as a part of the waste products of combustion from the incinerator unit.

It is also to be understood that the illustrative apparatus for producing the secondary combustion zone is likewise illustrative in character only. For example, the structure forming the secondary combustion zone as disclosed in my copending application Serial No. 37,772, filed June 21, 1960, now abandoned, may be employed equally as well with the heat exchanger assembly 50 of the present invention. By way of illustration, reference is now to be had to FIGS. 9 and 10 wherein a second form of apparatus for forming the secondary combustion zone is shown. The apparatus shown in FIGS. 9 and 10 for providing the secondary combustion zone comprises an inner cylindrical stack member 93 which is connected at its lower end to the exhaust outlet of the heat exchangers 50. The inner stack member 93 may be a conventional exhaust stack normally employed with incinerators and the like. The inner stack member 93 will extend upwardly through the frame support assembly 72 and be supported thereby, and will continue upwardly for a distance sufficient, with respect to the capacity of the incinerator and the volume of waste products of combustion produced therein, to carry off the waste products of combustion, but will not be of a height such that the third combustion zone cannot be efficiently formed.

An air inducer or blower fan, generally designated by

reference numeral 94, is mounted on the outside surface of the inner stack member 93 for access thereto about the normal discharge outlet of the heat exchanger. The blower fan 94 has access into the inner area of the inner stack member 93, and this may be accomplished by forming an opening in the stack which is in alignment with the operating opening of the blower fan 94. The draft inducer or blower fan 94 illustrated herein is of conventional design, and may be readily purchased on the open market. Accordingly, no detailed description thereof is believed necessary. It will suffice to say in connection with this that any mechanical means capable of continuously imparting a steady amount of air into the inner stack member 93 and at the same time effecting the desired draft inducement of the waste products of combustion may be employed in the present invention. The size of the blower fan 94 to be employed in the present invention will vary, depending upon the capacity of the burner unit proper as well as the diameter of the inner stack member 93. Accordingly, any size blower fan may be employed which will effect the desired draft inducement of the waste products of combustion and at the same time deploy a sufficient amount of air into the inner stack member 93 for admixture with the rising waste products of combustion.

As shown, the blower fan 94 takes air from the surrounding atmosphere, but it is also possible to connect the inlet end of the blower fan 94 by means of suitable piping, ducts, or the like, to one of the exhaust or outlet outlets of the air exhaust header 35 of the heat exchanger 31 such that extremely hot air will be blown into the exhaust stack at the secondary combustion zone.

An air guide member, generally designated by reference numeral 95, is employed in association with the air blower fan 94 to direct and control the direction of the air being drawn into the inner stack member 93 and to aid in the creation of the draft for the waste products of combustion. The air guide member 95 includes a plurality of upwardly inclined arcuate plates 96, 97, 98, and 99, each of which is vertically spaced from one another and is of diminishing length with respect to one another. Each of the upwardly inclined arcuate plates 96, 97, 98, and 99 is united along each side edge to side plates 100. The lateral width of the plates 96, 97, 98, and 99 is relatively short or narrow in order to create the desired air action, and present no deterrent to the normal upward flow of the waste products of combustion, as well as assisting in the creation of the desired draft of same. This construction results in a narrow, upwardly inclined arcuate, elongated plurality of passages in which the lower end of each is in association with the air blower 94, with each being vertically spaced one above the other through which air will be blown inwardly and upwardly for admixture with the products of combustion rising upwardly through the inner member 93 from the fire burning unit proper.

The illustrated air guide member 95 may be secured at opposed points to the inner surface of the inner stack member 93 by spot welding, brazing, bolting, or in any desired manner. Alternatively, the air guide member 95 may be bolted through the inner pipe member 93 to the housing of the air blower 94. The air guide member 95 may be made of any suitable metal, such as, for example, steel, cast iron, or similar metal. Preferably the metal employed should be of sufficient strength and heat resistance in order to impart a long wearing life thereto, particularly since it is in the immediate area in which the hot products of combustion rising from the heat exchanger 50 are ignited and the area immediately thereabove serves as a secondary combustion chamber in which high heat will be generated.

A small cylindrical fuel cup 101 is mounted to the inner surface of the inner stack member 93 and rests on the top surface of the air guide member 95 just above the inlet end of the blower fan 94. The fuel cup 101 is made of

any suitable metal, such as, for example, steel or the like, but must possess a sufficient high resistance to heat, since it is within this area that fuel is ignited to create the secondary combustion zone, in a manner to be described more fully hereinafter. The fuel cup 101 need not necessarily be mounted directly to the inner surface of the inner stack member 93, but may be inwardly spaced slightly therefrom and secured to the top edges of the side plates 100 of the air guide member 95 by welding or the like.

The fuel cup 101 is preferred in the present modification since it provides a small area in which the fuel may be injected and ignited without fear of any pre-ignition of the waste products of combustion and the air admixed therewith by means of the blower 94. That is to say, by the utilization of the fuel cup 101, there will be no ignition of the waste products of combustion until they reach the secondary combustion zone, which is in the immediate vicinity of the cup 101. However, it will be found possible under certain circumstances to eliminate the use of the fuel cup 101, such situations being where no pre-ignition of the waste products of combustion and air will create a problem. However, in general, a fuel cup 101 will be found advantageous to be included in the overall unit.

A fuel nozzle 102 for injecting the fuel within the fuel cup 101 is mounted to the bottom surface of the cup 101 and extends upwardly therein. The fuel nozzle 102 is of generally conventional design and is readily available on the open market, and therefore no detailed description of same is believed necessary. As shown, one end of the fuel nozzle 102 constitutes the fuel exit end which is within the fuel cup 101, while the opposite end, which is outside thereof, is secured to a fuel inlet line 103 which extends through the inner stack member 93 and is connected to a suitable fuel source (not shown). The fuel to be employed in the present invention and to be dispensed from the fuel nozzle 102 may be any fuel that can be imparted into the fuel cup 101 in a jet or atomized state. Suitable fuels meeting these requirements are conventional fuel oil and gas, although any liquid or gaseous fuel capable of being dispensed in the manner indicated may be employed.

The igniter means to ignite the fuel in this modified form of the invention shown in FIG. 9 may be the same igniter member 86 shown and described hereinbefore with the other form of the invention. The igniter member 86 may be mounted in the same manner as hereinbefore described with the spark gas end extending into the fuel cup 101 and resting above the discharge end of the fuel nozzle 102 to ignite the fuel in the same manner as hereinbefore described.

To achieve the third combustion zone, the same assembly hereinbefore described with respect to one form of the invention will be the same in the modified form herein described. As illustrated in the modification, the outer upper stack 89 is secured to the inner stack member 93 above the secondary combustion zone in spaced relationship therewith by means of connecting rods 90 extending therethrough at various convenient points. Thus the construction for producing the third combustion zone and the operation thereof to produce same will be identical in both forms of the invention illustrated herein. The foregoing description of the modified form of apparatus for producing the secondary combustion zone has been had with respect to only one such assembly. However, it is to be clearly understood that the assembly will be duplicated for each heat exchanger employed with the incinerator.

The heat exchanger assembly 31 mounted within the building unit 10 has been illustrated as providing means for imparting extremely hot fresh air to the outlet stack or pipe 70 for utilization in the secondary combustion zone. However, the heat exchanger unit 31 is capable of performing other functions. For example, if the hot

fresh air formed in the heat exchanger 31 is not to be imparted to the outlet stack 70 or the inner stack 93 to support the secondary combustion zone, the hot air can be employed to heat any given area in the manner of the heat exchanger 50. This is possible by providing an air outlet header in place of header 35 which will be open only at one end with the opening being connected to suitable duct work for transmission of the heated air to any given area to heat same.

10 Alternatively, water may be the medium passed through the heat exchanger 31 to effect the production of hot water which may then be transmitted from the exhaust end of the outlet header to any desired point for storage or for use.

15 While the foregoing description of one illustrative embodiment of the invention has been shown utilizing only an inner stack 88 and an outer stack 89 for each heater exchanger 50, it is to be clearly understood that an additional stack may be employed for each heat exchanger.

20 The utilization of an additional or second outer stack will be found advantageous with certain types of incinerators having a large capacity, and where excessive and intense heat is generated over a period of time in the incinerator unit and correspondingly in the exhaust stacks

25 88 and 89. The creation of high heat in the stack units over a period of time will result in considerable loss of heat to the atmosphere due to radiation which otherwise could be utilized to increase the efficiency of the unit.

Reference is now to be had to FIG. 12 wherein a modification utilizing second outer stacks is shown. In the ensuing description like numerals will be employed in designating identical parts used in the form of the invention previously described. As illustrated, the refractory

30 roof 41 has the exhaust openings 42 positioned therein in spaced relation and the pair of heat exchangers 50 connected thereto in the same manner as hereinafter described. Similarly, each heat exchanger 50 is provided with an outlet pipe or stack 70 which extends upwardly to an expansion collar 71 mounted to the frame support

35 72. Each of the outlet pipes 70 immediately adjacent its connection with the expansion collar is provided with an air guide member generally designated by reference numeral 95, a fuel burning cup 101, and igniter means 86 and 87 to provide a secondary combustion zone. This 40 construction is at the area of the secondary combustion zone and is shown in detail in FIGS. 9 and 10 and will operate in the same manner in this form of the invention. As in the form previously described, an inner stack 88 and an outer stack 89 are connected to each pipe 70 and will 45 function in the same manner as hereinbefore described with other forms of the invention.

45 A second outer stack 160 in the modification shown in FIG. 12 is placed in spaced, circumferentially enveloping relationship around each of the outer stacks 89, and 50 will be secured thereto by conventional spanner rods 161, ribs, or the like. Each of the second outer stacks 160 has its upper free end 162 terminating at a point below the upper free end of each of the outer stack members 89 and below the conventional rain cap 163

55 normally mounted on chimney stacks of this character. The purpose of having the upper end 162 of each of the second outer stacks 160 below the upper free end of each of the outer stacks 88 is to enable air to be drawn into the space formed between the second outer stack 160 and outer stack 88. The bottom free end of each of the second outer stacks 160 is closed and rendered airtight by a transversely extending cover plate 164 or the like, which is secured to the bottom circumferential edge 60 of each of the second outer stacks 160 and to the outside surface of the outer stack member 89. This construction results in a completely airtight, cylindrical chamber between each of the second outer stacks 160 and each of the outer stacks 88, with the entrance to each being provided by the upper free end 162 of the second outer

65 stack 160.

An outlet exit opening 165 is provided in each of the second outer stacks 160 immediately adjacent the bottom end thereof, and will function as the air outlet means for the air drawn down into each of the formed cylindrical chambers from the entrance at the free end 162 above. The outlet opening 165 in each of the second outer stacks 160 is provided with pipe outlet means generally designated by reference numeral 166 which extends from the outlet opening 165 of each of the second outer stacks 160 to an air blower 167 which will function as the means for transmitting the air from each of the enclosed chambers of each stack for admixture with the exhaust gases rising upwardly from the heat exchanger 50 to the second combustion zone therein.

In the illustrative embodiment shown in FIG. 12, the pipe outlet means 166 present therein exemplify another form of means for imparting air into the second combustion zone, which has not been shown hereinbefore. The pipe outlet means 166 comprise a cross-pipe member 168 having its opposite free ends connected to the outlet end 165 of each of the second outer stacks 160 by any suitable means, such as, for example, welding, threading, etc. The cross-pipe member 168 is connected substantially at its mid-point to the upper free end of a vertical pipe member 169 of a diameter greater than that of the cross-pipe member 168. The opposite free end of the vertical pipe member 169 is connected to the inlet side of the blower 167. This construction defines a pipe arrangement that is T-shaped in configuration with the opposite ends of the cross-pipe element being open and an open end at the lower free end of the vertical pipe element which permits the withdrawing of hot air from each of the second outer stacks 160 and mixing and converging same into a single pipe 169 connected to the air blower 167.

The air inlet pipe means, generally designated by reference numeral 170, is connected to the outlet side of the air blower 167 for transmitting heated air into the second combustion zone. The air inlet pipe means 170 include a vertical outlet pipe 171 connected at one end to the discharge side of the blower 167, with the opposite end connected to substantially the mid-point of a cross-pipe element 172 which is of a diameter less than that of the vertical outlet pipe 171. The opposite free ends of the cross-pipe element 172 are connected respectively to the inlet side of the air guide member 95 of each outlet pipe means 70 of each stack for transmitting the hot air to the second combustion zone of each stack. This construction defines an inverted T-shaped unit for collecting the hot air from the blower and dividing same into two air streams, one for each stack.

It is to be clearly understood that the foregoing description of one modification employing two outer stacks and the associated outlet pipe means for distributing the air to the secondary combustion zone is for illustrative purposes only and exemplifies only one form of the invention utilizing the two outer stacks for transmitting the heated air to the secondary combustion zone. For example, the air contained in the second outer stack of each stack unit need not be brought in and distributed by a common blower. Rather, each stack unit may be provided with an individual blower connected at one end to the air guide means 95, with the opposite end of each being coupled to the discharge outlet 165 carried in the second outlet stack 160 of each stack unit. Thus it is believed obvious that there are several ways to transmit air in the formed chamber between each of the outer stacks 160 and 89 to the secondary combustion zone. Further, such air may be directed into the secondary combustion zone by means other than the air guide means 95 and its associated parts as shown in FIGS. 9 and 10.

The operation of the modified form shown in FIG. 12 to achieve the second and third combustion zones is basically the same as hereinbefore described. The waste material, when burned in the incinerator, transmits heat

and waste products of combustion to the heat exchangers 50. The waste products of combustion then pass up through the exhaust stack to the second combustion zone and hence to the third combustion zone in identically the same manner as hereinbefore described with other forms of the invention. When the outer stack 89, after a period of operation, becomes quite hot, heat will be transmitted to the second outer stack 160 likewise placing each of these second outer stacks in a heated state. Air will be drawn downwardly through the upper free end 162 of the second outer stack 160 into the formed chamber between the second outer stack 160 and the outer stack 89 of each stack unit. During the downward passage of the air, it will become quite hot due to radiation. The heated air is drawn out of the outlet 165 of each of the formed air chambers of each stack by the blower 167, through the top cross pipe 168 and into the vertical pipe 169. Thus heated air is drawn from each enclosed chamber of each stack unit and is blended and admixed with one another by the blower.

The blower 167 passes the entire volume of the heated air collected from each of the stack units through a vertical inlet pipe 171. The heated air is then divided in the lower vertical pipe 172 with substantially equal parts thereof being passed to the air guide member 95 of each unit. This operation results in the transmittal of extremely hot, fresh air to the secondary combustion zone, thereby materially increasing the efficiency of the secondary combustion zone with a resulting greater consumption of the waste products of combustion at this zone.

It will also be found advantageous with respect to large incinerator units having a large capacity in which large quantities of waste products of combustion are generated to provide means to insure a prompt and complete throughput of such waste products of combustion to the second combustion zone to effect the consumption thereof. There are several ways by which this can be accomplished. For example, as shown in the illustrative embodiment of the invention, each heat exchanger unit 50 is provided with a single exhaust outlet 60 and a single exhaust pipe outlet 70. This construction constitutes the sole discharge outlet for the waste products of combustion generated in the incinerator. To provide additional auxiliary exhaust means for transmitting the waste products of combustion from the heat exchanger 50 to the second combustion zone an outlet opening may be provided on each side of the central discharge outlet 69 of the heat exchanger in slightly spaced, lateral relationship thereto. Each side auxiliary outlet opening 50 will be provided with pipe means which extend upwardly therefrom and then inwardly to the connecting pipe 70 or the inner stack member 88 at a point at or just above the fuel outlet 102 in the outer stack 88 or the connecting pipe 70.

This construction results, in addition to the single main exhaust outlet, additional exhaust means for insuring the complete and prompt passing of the hot waste products of combustion upwardly from the heat exchanger 50 and then into the inner stack 88 or the connecting stack 70 at the secondary combustion zone where same is burned therein. It is not necessary for auxiliary side outlets to have the waste products of combustion carried thereby fed into the secondary combustion zone at its initial point of formation. For example, the waste products of combustion carried by the auxiliary side outlets from each of the heat exchangers may be carried into the exhaust stack 88 at a point above the initial formation of the secondary combustion zone. The reason for this is that the secondary combustion zone when in operation will transmit heat over an area sufficiently large to ignite the waste products of combustion being fed thereto by the auxiliary pipes at a point above the initial formation of the secondary combustion zone.

Reference is now to be had to FIGS. 1, 3, and 11

wherein the apparatus in which a waste receptacle apparatus, generally designated by reference numeral 110, is shown. The waste receptacle apparatus 110 functions as the means for transporting the material to be burned into and out of the building unit 10, thereby insuring that the waste material during burning will not come into actual contact with the side walls and end walls of the building unit 10.

The waste receptacle apparatus 110 includes a base frame support, generally designated by reference numeral 111, having a pair of spaced, parallel, downwardly turned U-shaped, lower channel members 112 which are spaced apart from one another for a distance substantially equal to the distance between the pair of rails 13 extending along the floor 11 of the building unit 10. A plurality of pairs of mounting plates 113 are connected to the downwardly extending flanges of the U-shaped channel members 112 with the bottom end of each pair of mounting plates 113 being provided with axially aligned openings therein in which wheel stub shafts 114 are mounted to serve as a means for mounting a wheel 116 to each pair of mounting plates 113. The wheels 116 are flanged wheels of the type that will run on the rails 13. This construction results in a plurality of spaced wheels 116 which will be mounted on the tracks 13 to move the receptacle apparatus 110 into and out of the building unit 10.

The bottom frame support elements 112 are connected to one another by a plurality of top transversely extending U-shaped structural frame elements 117 which are secured to the top surface of the bottom frame support 112 by welding, bolting, or the like, and lie in a vertical plane with respect thereto. The top U-shaped structural frame elements 117, in addition to functioning as connecting links for the bottom frame support elements 112, will be associated in pairs in order to provide means for receiving ash drawers 118 therein. As illustrated, one transversely extending U-shaped top frame element 117 is secured immediately adjacent the front end of each of the bottom support frame elements 112 with the flange portions thereof extending inwardly and rearwardly. The next transversely extending U-shaped top frame element to connect the bottom frame elements 112 is so positioned on the top surface thereof that the respective flange portions thereof will extend forwardly in the direction of the flange portions of the first or front support frame element 117, thereby defining opposed side channels into which ash drawers 118 may be removably positioned along each side thereof in a manner to be more fully described hereinafter. Any number of desired pairs of transversely extending top frame elements 117 may be employed in this manner which will be sufficient to impart the desired strength to the waste receptacle 110 and yet provide a sufficient number of pairs of frame elements for an adequate number of ash drawers 118. In general, a sufficient number of pairs of top, transversely extending frame elements 117 will be employed to provide a sufficient number of receptacles 118 to extend beneath the entire surface of the waste receptacle assembly to receive burned residue therein, thereby enabling the ready withdrawal of such material without breaking down the receptacle or climbing thereinto. Such advantages will be more apparent from the description given hereinafter.

A plurality of short, vertical support pipe elements 119 are secured to the outside faces of the front and rear transversely extending U-shaped support elements 117 respectively in vertical alignment with the front and rear ends of each of the bottom support elements 112, with the upper free ends of the vertical pipe support elements 119 extending above the top surface of the upper support elements 117. This assembly results in four open ended spaced pipe receptacles extending upwardly from the top surface of the upper support elements 117, and which will serve as means for mounting the basket portion of

the receptacle to the support frame assembly 111 in a manner to be more fully described hereinafter. Transversely extending pipes 115 will be secured to the top surface of the transversely extending frame elements 117 with the outside diameter being equal to the height to which the vertical pipe elements 119 extend above the top surface of top frame elements 117.

The foregoing assembly just described defines a supporting base assembly 111 on which a basket assembly, generally designated by reference numeral 120, will be carried in detachable relationship therewith. The basket assembly 120 will possess a configuration substantially identical with and of substantially the same dimensions as the base frame support assembly 111, and includes front and rear header pipes 121 and 122 which extend in transverse relationship to the bottom U-shaped frame support elements 112, and are in substantially parallel relationship with one another. The front header pipe 121 is provided with a pair of spaced, outwardly extending pipe nipples 123 which are so spaced with respect to the front transversely extending header 121 that they will extend downwardly into the vertical pipes 119 secured to the transversely extending U-shaped frame elements 117 and will be in detachable relationship therewith. The rear transversely extending header pipe 122 likewise is provided with downwardly extending pipe nipples 123 which are so positioned thereon that they will slide into the pipes 119 on the rear transversely extending support elements 117. This construction will result in the front and rear header pipes 121 and 122 of the basket assembly 120 secured to the frame assembly 111 in vertically spaced relationship therewith, and yet be in detachable relationship therewith.

A plurality of spaced pipe nipples 124 are positioned along each rear face of the front header 121 and extend rearwardly therefrom. Similarly, the rear, transversely extending header 122 is provided with a plurality of like nipples 124 which extend inwardly or forwardly in the direction of the pipe nipples 123 of the front header 121 and are in axial alignment therewith. The pipe nipples 124 are not threaded but extend into the front header 121 and the rear header 122 for passage of air into each of the headers 121 and 122, as will be described more fully hereinafter. Each of the pipe nipples 124 of the front header 121 is connected to a corresponding pipe nipple 124 connected on the rear header 122 by pipes 125. The pipes 125 have a diameter such that each free end of each pipe will be positioned within the pipe nipples 124 by a slip joint connection. The advantage of this arrangement is that during the time when intense heat is being generated in the incinerator, the side pipes 125 will be able to expand within the pipe nipples 124. Each of the pipes 125 has its upper surface provided with a plurality of holes 125a therein through which air will be passed upwardly to support combustion during the burning of the waste material. The pipes 125 will also rest on the top surface of the transverse pipes 115 thereby further supporting them.

An air inlet coupling pipe 127 extends rearwardly from the side of the rear header 122 and functions as the means for transmitting air into the rear header 122, and hence through the pipes 125 and out of the openings 125a formed therein to support the combustion of the waste materials to be burned. The air inlet coupling pipe 127 is so positioned with respect to the rear header 122 that when the cart assembly 110 is positioned within the building unit 10, it will seat in an air supply line 128 which extends through the rear wall 16 of the building unit 10 with the opposite end of the air line being connected to an air blower 129 or other air supply means. To assist in the proper and automatic coupling of the air coupling line 127 and the air inlet line 128, the forward free end of the air inlet pipe 128 within the building unit 10 is provided with an outwardly flared funnel element 130, there-

by insuring the proper coupling of the two lines upon the movement of the cart assembly 110 into position.

Each corner of the front and rear headers 121 and 122 is provided with vertically extending pipe nipples 131 which may extend into the inner area of each of the leaders 121 and 122 in the event air is to be transmitted upwardly in further support of the combustion of the material during burning, or, if desired, may be merely welded or otherwise secured to the outside surface of the headers 121 and 122 and the side pipes 124. The function of these vertically extending pipe nipples 131 is to enable the attachment of the basket framework to the bottom frame assembly. To accomplish this, vertically extending frame pipe elements 132 are provided at each corner of the headers 121 and 122 and extend upwardly therefrom in vertical relationship with respect thereto. The vertically extending frame pipe elements 132 are held in engagement therewith by slipping each over the pipe nipples 131 by a slip joint connection which will permit expansion between the associated elements during the burning of waste material in the incinerator.

The vertically extending frame pipe elements 132 are connected to one another by a plurality of vertically spaced, horizontally extending frame pipe elements 133 which results in an extremely rigid, open, basket frame. The horizontally extending frame pipe elements 133 are shown as being welded at each end to the vertically extending frame pipe elements 132. However, it is to be understood that this may be accomplished by employing a slip joint connection at each association in order to allow for expansion during the burning of waste material or to permit the flow of air therein. In the event of the latter, the horizontal pipe elements 133 will have access into the inner area of the vertical pipe elements 132 which, in turn, will have access into the inner area of the headers 121 and 122 thereby forming a closed air system not only through the bottom pipes 125 but also at one or more levels thereabove. In such a construction, the horizontal pipe elements 133 and also, if desired, the vertical pipe elements 132 will be provided with openings facing inwardly to permit air to be blown into the area defined by the basket assembly.

With further regard to the distribution of air into the basket assembly above its bottom level, it is to be noted that more than one air inlet assembly may be employed. For example, the rear wall 16 may be provided with another opening vertically spaced upwardly from the opening 17 shown therein and will be so positioned as to be in horizontal alignment with one of the rear horizontally extending pipe elements 133 and positioned midway between the vertical pipe elements 132. The rear and the front horizontally extending pipe elements 133 extending along this midpoint level will be in the form of headers with the two horizontally extending pipe elements at this level being connected thereto in the same manner as the bottom pipes 125 are to the headers 121 and 122. The rear horizontally extending pipe element functioning as a header will be provided with a rearwardly extending air pipe line element which will be capable of engaging or coupling with an air inlet coupling mounted in the opening in the rear wall 16 and which is, in turn, connected to an air blower positioned outside the building unit 10. This construction results in two vertically spaced air inlet levels to support the combustion of the waste materials to be burned. It should be noted that in this modification, the upper air blower should operate at a relatively high pressure and the lower air blower should operate at a lower pressure for best results.

If desired, additional vertical reinforcing rods 134 may be secured by welding or the like to the outside surface of the horizontally extending pipe support element 133 at convenient points therealong. It will be found advantageous to provide an open frame work mat 136, which may be in the form of a diamond mesh construction, on the top upper surface of the pipes 125. Similarly, the two

side walls and the rear wall of the basket assembly 120 will be provided with similar open framework mats 137 which likewise may be of a diamond mesh construction. The purpose of the mats 136 and 137 is to retain all types of material regardless of the size within the basket assembly 120 during burning. Moreover, the bottom open mesh mate 136 will serve to prevent any large pieces of residue remaining after burning from shifting downwardly into the ash drawers yet will permit ash and small pieces to sift therethrough into the drawers 118. A heat baffle plate 138 in the form of a metal sheet may be secured to the front face of the basket assembly to prevent heat being directed outwardly toward the doors. The heat baffle plate 138 may have its upper edge outwardly curved forming a hook portion which will fit over the front top horizontally extending pipe element 133 with the remaining portion of the plate resting against the inside front face of the basket assembly.

No electrical controls have been shown in any of the embodiments of the invention hereinbefore described. However, such controls to be employed in the present invention are conventional, and are readily available on the open market. Such controls to effect the operation of the various blowers and like electrical parts may be positioned at any point or location on the incinerator, as desired.

In the operation of the illustrative embodiment of the incinerator herein made in accordance with the present invention, the waste material to be burned is placed in the waste receptacle apparatus 110. The receptacle apparatus 110 after being fully loaded is pushed in on the rails 13 into the building unit 10 until the air pipe element 127 of the receptacle 110 engages and is coupled with the air inlet pipe 128 extending through the rear walls 16 of the building unit 10. This operation places the unit 10 in a state ready for operation to effect the burning of the waste material. The waste material is ignited and doors 21 and 22 of the building unit 10 are closed thereby sealing the building unit 10.

The air blower 129 connected to the air inlet pipe 128 is set into operation to blow air under pressure into the rear header pipe 122 of the receptacle 110, and hence through the pipes 125. The air blowing through the rear header pipe 122 and out through the openings 126 in the pipes 125 will provide sufficient oxygen to effect an efficient and rapid burning of the waste material in the receptacle apparatus 110 regardless of the volume of the waste material. Moreover, the introduction of the air in this manner to support the combustion will provide a constant cooling of the pipes 125 such that they will not burn out readily. This manner of providing air for support of combustion to effect the burning of the waste material results in the hottest zone being always adjacent the bottom of the cart assembly. Thus the waste material sifts downwardly as the material is being burned. This will provide advantageous not only in effect an efficient and rapid burning, but also results in the ashes and other residue shifting downwardly continuously into the ash receptacles 118. This operation facilitates the ultimate removal of the ashes upon the completion of the burning.

During the initial commitment of the burning of the waste material in the building unit 10, the blower 34 on the air inlet header 33 of the heat exchanger 31, as well as the blowers 62 of the heat exchangers 50 are set into operation. The heat, smoke, and other waste products of combustion generated in the incinerator during the burning of the waste material therein passes upwardly filling the entire upper area of the building unit 10, and surrounds the pipes 32 of the heat exchanger 31, thereby heating, through heat transfer relationship, the air being blown through the pipes 32 by means of the air blower 34. This operation will result in hot air passing outwardly from the pipes 32 into the air outlet header 35 for use in

support of this secondary combustion zone, as will be described more fully hereinafter.

The heat and waste products of combustion pass upwardly and out from the building unit 10 through the outlets 42 positioned in the roof 41, and into the heat exchangers 50 to the pairs of spaced outlet pipes 47, and into the heat trap member 64. The heat exchangers 50 will continuously heat the air being blown therethrough by means of the blower 62 in transvers relationship to the flow of the smoke and heat from the incinerator. The heat and smoke which constitute the waste products of combustion follow the tortuous path in the heat exchanger housing 50 in the manner hereinbefore described, and will reach the exit end or top outlet on the top surface of the outlet shell body 53. The heat and waste products of combustion pass out of the heat exchangers 50 through the outlets 69 into the outlet pipes 70. As such waste products of combustion and heat rise upwardly in the pipes 70, they will come into intimate contact with the mixture of hot gases coming from the heat exchanger 31 and the fuel coming into pipe 70 through the air mixture fuel assembly 75, and will be intimately admixed therewith. The admixture of waste products of combustion and the fuel-air mixture is ignited and burned by the igniter 86. The burning of the mixture of fuel-air and waste products of combustion creates a secondary combustion zone in which the waste products of combustion are further burned, with such burning resulting in an extremely high temperature being created at this secondary combustion zone.

The waste products of combustion rise upwardly from the secondary combustion zone through the inner outlet pipe 88 and are admixed with the air rising upwardly between the inner outlet pipe 88 and the outer stack pipe 89 at the exit end of the inner outlet pipe 88. As the air passes upwardly in the formed passageway between the inner pipe 88 and the outer pipe 89, the air will be readily heated by the heat transfer relationship with the surface of the inner pipe 88. Thus when the air mixes with the waste products of combustion of the secondary combustion zone at the exit end of the inner pipe 88, the mixture effects a self-ignition with a corresponding further burning of the remaining waste products of combustion being obtained. This further burning in the third combustion zone results in a substantially complete burning of the remaining waste products of combustion and the products therefrom will rise upwardly and outwardly through the outer pipe 89 and into the atmosphere in a state which is not objectionable.

Upon completion of the burning of the waste material in the receptacle apparatus 110, the doors 21 and 22 of the building unit 10 are opened, and the receptacle apparatus is withdrawn therefrom. It will be found, due to the manner of supplying air to the burning zone of the incinerator, that the receptacle apparatus 110 can be handled without first permitting same to be cooled. The ash drawers 118 are emptied and the large particles not otherwise capable of being burned, if any are present, may be removed. The receptacle 110 is then refilled with waste material to be burned and reinserted in the building unit 10. This operation is continued until all of the waste material to be destroyed has been burned.

While there have been described herein what are at present considered preferred embodiments of the invention, it will be obvious to those skilled in the art that modifications and changes may be made therein without departing from the essence of the invention. It is therefore to be understood that the exemplary embodiments are illustrative and not restrictive of the invention, the scope of which is defined in the appended claims, and that all modifications that come within the meaning and range of equivalency of the claims are intended to be included therein.

I claim:

1. An incinerator construction comprising a building unit having a floor, side walls, rear wall, door means and a roof, spaced track means in the floor of said building unit, cart means for receiving material to be burned mounted on said track means for movement into and out of said building unit, said cart means including a plurality of hollow pipe means connected to one another defining a pair of side walls and front and rear walls, at least one of said pipe means having a plurality of openings axially spaced therealong for directing air inwardly within the cart means, one of said pipe means forming said rear wall of said cart means having at least one nipple extending outwardly therefrom in substantially right angled relationship to the rear wall of said building unit, air inlet means in said rear wall of said building unit for detachable, axial engagement with said nipple of said rear wall of said cart means for passage of air through the pipes forming said cart and out through the plurality of openings to support combustion of the material to be burned, at least one outlet means in said roof for passage of the waste products of combustion therethrough, and exhaust means secured to said outlet means.

2. An incinerator construction comprising a building unit having a floor, side walls, rear wall, door means and a roof, spaced track means in the floor of said building unit, cart means for receiving material to be burned mounted on said track means for movement into and out of said building unit, said cart means including a plurality of hollow pipe means connected to one another defining a pair of side walls and front and rear walls, at least one of said pipe means having a plurality of openings axially spaced therealong for directing air inwardly within the cart means, one of said pipe means forming said rear wall of said cart means having at least one nipple extending outwardly therefrom in substantially right angled relationship to the rear wall of said building unit, air inlet means in said rear wall of said building unit for detachable, axial engagement with said nipple of said rear wall of said cart means for passage of air through the pipes forming said cart and out through the plurality of openings to support combustion of the material to be burned, heat exchanger means mounted in said building unit immediately below said roof, at least one outlet means in said roof above said heat exchanger means for passage of the waste products of combustion therethrough, and exhaust means secured to said outlet means.

3. An incinerator construction comprising a building unit having a floor, side walls, rear wall, door means and a roof, spaced track means in the floor of said building unit, cart means for receiving material to be burned mounted on said track means for movement into and out of said building unit, said cart means including a plurality of hollow pipe means connected to one another defining a pair of side walls and front and rear walls, at least one of said pipe means having a plurality of openings axially spaced therealong for directing air inwardly within the cart means, one of said pipe means forming said rear wall of said cart means having at least one nipple extending outwardly therefrom in substantially right angled relationship to the rear wall of said building unit, air inlet means in said rear wall of said building unit for detachable, axial engagement with said nipple of said rear wall of said cart means for passage of air through the pipes forming said cart and out through the plurality of openings to support combustion of the material to be burned, at least one outlet means in said roof for passage of the waste products of combustion therethrough, exhaust stack means secured to said outlet means, and heat exchanger means associated with said stack means, said heat exchanger means being in substantially right angle relationship to the flow of the waste products of combustion through said stack means.

4. An incinerator construction comprising a building unit having a floor, side walls, rear wall, door means and

a roof, spaced track means in the floor of said building unit, cart means for receiving material to be burned mounted on said track means for movement into and out of said building unit, said cart means including a plurality of hollow pipe means connected to one another defining a pair of side walls and front and rear walls, at least one of said pipe means having a plurality of openings axially spaced therealong for directing air inwardly within the cart means, one of said pipe means forming said rear wall of said cart means having at least one nipple extending outwardly therefrom in substantially right angled relationship to the rear wall of said building unit, air inlet means in said rear wall of said building unit for detachable, axial engagement with said nipple of said rear wall of said cart means for passage of air through the pipes forming said cart and out through the plurality of openings to support combustion of the material to be burned, heat exchanger means mounted in said building unit immediately below said roof, at least one outlet means in said roof above said heat exchanger means for passage of waste products of combustion therethrough, exhaust stack means secured to said outlet mean, and heat exchanger means associated with said stack means, said heat exchanger means being in substantially right angle relationship to the flow of the waste products of combustion through said stack means.

5. An incinerator construction comprising a building unit having a floor, side walls, rear wall, door means and a roof, spaced track means in the floor of said building unit, cart means for receiving material to be burned mounted on said track means for movement into and out of said building unit, said cart means including a plurality of hollow pipe means connected to one another defining a pair of side walls and front and rear walls, at least one of said pipe means having a plurality of openings axially spaced therealong for directing air inwardly within the cart means, one of said pipe means forming said rear wall of said cart means having at least one nipple extending outwardly therefrom in substantially right angled relationship to the rear wall of said building unit, air inlet means in said rear wall of said building unit for detachable, axial engagement with said nipple of said rear wall of said cart means for passage of air through the pipes forming said cart and out through the plurality of openings to support combustion of the material to be burned, heat exchanger means mounted in said building unit immediately below said roof, said heat exchanger means including a plurality of pipes extending through each side wall of said unit, an air inlet header means connected to one end of said pipes on the outside face of one of said side walls, air blower means at one end of said inlet header, and an air outlet header connected to the other end of said pipes on the outside face of the opposite side wall of said building unit, at least one outlet means in said roof above said heat exchange means for passage of waste products of combustion therethrough, and exhaust means secured to said outlet means.

6. A waste receptacle apparatus for use in an incinerator construction comprising a base frame means, wheel means secured to the bottom of said base frame means, a plurality of vertically extending first short support pipe means secured to said frame means and extending above the top surface of said base frame means, basket base means including a front header pipe, a rear header pipe and a plurality of spaced, parallel pipes operatively connecting said front and rear header pipes, at least one of said plurality of pipes having a plurality of openings therein, and air inlet nipple means connected to said rear header means providing access thereto, a plurality of vertically extending second short pipe support means secured to said front and rear header pipes and extending below said header pipes, said second pipe support means being in registered relationship with said first pipe means, and a frame basket member mounted on said basket base member.

7. A waste receptacle apparatus for use in an incinerator construction comprising base means, means connected to said base means to permit same to be moved into and out of said incinerator construction, basket means mounted on said base means, said basket means including front header means, rear header means in spaced parallel relationship to said front header means, a plurality of spaced, parallel pipes operatively connecting said front and rear header means, at least one of said plurality of pipes having a plurality of openings therein, air inlet means connected to said rear header means to permit air to be blown into said front and rear headers and said plurality of pipes, front and rear frame means and side frame means connected to one another and at least to said front and rear header means.

8. Apparatus for permitting the emission of waste products of combustion to the atmosphere in an unobjectionable state comprising first, inner exhaust stack means adapted to be secured at its lower end to the exhaust outlet of a fire burning apparatus, air supply means secured to said first stack means adjacent its lower end to supply air thereto, fuel dispensing means secured to said stack means adjacent said air supply means, ignition means for igniting said fuel to effect an initial burning of the waste products of combustion in the lower end of the inner stack means, a second stack means secured to said inner stack means in circumferentially spaced, enveloping relationship, the lower end of said second stack means being spaced above said fuel supply means with the upper end thereof terminating at a point above the upper free end of said first stack means thereby defining an air passageway therebetween of substantial length along which air will be drawn, a third stack means secured to said second stack means in circumferentially spaced, enveloping relationship forming an air passageway therebetween, the lower end of said third stack means being closed and spaced above the lower end of said second stack means, the upper end of said third stack means terminating below the upper end of said second stack means, and means connecting the lower portion of said third stack means to said air supply means.

9. Apparatus in accordance with claim 8 wherein said air supply means comprises a plurality of narrow arcuate plate means of diminishing length vertically spaced from one another, side members uniting said plate means along each side edge thereof, said side members spanning the internal diameter of said first stack means, and air blowing means mounted on the outside of said first stack means in association with said plate means to blow air into and up through said plate means.

10. Apparatus for permitting the emission of waste products of combustion to the atmosphere in an unobjectionable state from fire burning apparatus having a heat exchanger disposed within the fire burning apparatus comprising, first inner exhaust stack means adapted to be connected at its lower end to the exhaust outlet of the fire burning apparatus, air supply means secured to said first stack means adjacent its lower end to supply air thereto, fuel dispensing means secured to said stack means adjacent said air supply means, ignition means for igniting said fuel to effect an initial burning of the waste products of combustion in the lower end of the inner stack means, a second stack means secured to said inner stack means in circumferentially spaced, enveloping relationship, the lower end of said second stack means being spaced above said fuel supply means with the upper end thereof terminating at a point above the upper free end of said first stack means thereby defining an air passageway therebetween of substantial length along which air will be drawn, a third stack means secured to said second stack means in circumferentially spaced, enveloping relationship forming an air passageway therebetween, the lower end of said third stack means being closed and spaced above the lower end of said second stack means, the upper end of said third stack means

terminating below the upper end of said second stack means, and means connecting the lower portion of said third stack means to said air supply means.

11. Apparatus in accordance with claim 10 wherein said air supply means comprises a plurality of narrow arcuate plate means of diminishing length vertically spaced from one another, side members uniting said plate means along each side edge thereof, said side members spanning the internal diameter of said first stack means, and air blowing means mounted on the outside of said first stack means in association with said plate means to blow air into and up through said plate means.

12. Apparatus in accordance with claim 19, which further includes means for connecting the discharge end of the heat exchanger means mounted within the fire burning apparatus to said air supply means.
